UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

SEWING-MACHINE.

1,229,328.

Specification of Letters Patent. Patented June 12, 1917.

Application filed January 27, 1914. Serial No. 814,631.

To all whom it may concern:

Be it known that I, AUGUST R. SCHOENKY, a citizen of the United States, residing at Somerville in the county of Middlesex and State of Massachusetts, have invented certain new and useful Improvements in Sewing-Machines, of which the following is a specification, reference being had therein to the accompanying drawing.

This invention relates to sewing machines, and for convenience the invention is illustrated in connection with that type of machine used in the manufacture of shoes by the welt system for stitching together the outsole and welt.

In this class and other classes of sewing machines it is sometimes provided that the presser-foot be clamped or locked upon the work. For example, it may be intermittently clamped and released during the stitching of a shoe, the feed of the work occurring when the clamping pressure is released and the operation of the needle and awl occurring when the presser-foot is locked under clamping pressure. In such a case, there will be means for imposing a light pressure upon the presser-foot alternately with the heavy clamping or locking action.

When such a sewing machine is brought to rest by any stop mechanism or device operated either at will or upon an emergency or otherwise, the presser-foot will be incapable of being lifted to extract the work, if locked under the heavy clamping pressure.

It is an object of this invention to provide for the release of the pressure-foot from the clamping or locking action upon the stoppage of the machine in any manner, and particularly to effect this result during the operation of the stopping devices of the machine. Other objects hereof will be developed during the hereinafter following description of one illustration of a machine embodying the invention.

To the attainment of such objects, the invention consists in the novel combinations, mechanisms, devices, arrangements and other features described or shown herein.

Figure 1 is a front elevation of a shoe outsole sewing machine in which the present invention has been incorporated, the parts

being shown in their proper adjustment when the machine is in full operation.

Fig. 2 is a partial right elevation, and 55 part section taken upon the plane 4—4 of Fig. 1, the parts being in running adjustment.

Fig. 3 shows the lever 121 detached from the other parts in Fig. 2.

Fig. 4 is a view similar to Fig. 2 showing 60 the parts in their adjustment when the machine has been brought to rest.

Fig. 5 is a plan view, partly in section, on the plane 5—5 of Fig. 1.

Fig. 6 is a partial front elevation on an 65 enlarged scale of the mechanism seen in Fig. 5.

Fig. 7 is a vertical section taken upon the plane 7—7 of Fig. 5 or Fig. 6.

Fig. 8 shows the face of the toothed stop 70 cam 69.

Fig. 9 is a right elevation of certain parts shown in Figs. 2, 3 and 4, illustrating certain features in detail, and Fig. 10 is a front elevation of the parts shown in Fig. 9. 75

Similar reference numerals designate corresponding parts in the several views.

The illustrated machine comprises, in connection with the stitching mechanism, the driving mechanism therefor, and the stopping devices, a means brought into action by the stoppage of the machine for effecting the unlocking or unclamping of the presser-foot, thus permitting the extraction of the work; and in connection with these parts 80 is shown a treadle or lever which may be depressed or thrown for elevating the presser-foot after the stoppage of the machine. These parts co-operate in that the presser-foot releasing means unlocks the 85 presser-foot, thereby afterward permitting the treadle to lift the presser-foot, where otherwise the illustrated treadle would be unable to effect this operation.

Referring in detail to the illustrated machine, 11 indicates the vertical post of the machine supported on legs 12 and at its upper end supporting the irregularly shaped head in which the horizontal main shaft 13 is supported by means of bearings 14. The 100 shaft 13 has a hand wheel 15 at the left end and a plurality of cams embodied in three cam disks 16, 17 and 18. It will be understood that normally the main shaft is contin-

uously running and operates through the cams to effect the movements of the needle and other parts of the stitching mechanism.

- The details of the stitching mechanism 5 need not be described fully, since they *per se* form no part of the present improvement. However, the following parts will be referred to. There is shown a rotary shuttle 19, whose bobbin is confined by a swinging 10 bobbin retainer 20. Beneath the shuttle is a work-support 23 over which stands the presser-foot 24 which, for convenience, takes the form of a swinging arm, permitting it to be held upon the work or lifted from the 15 work. At the foot of the machine is shown a treadle 32 from which extends upwardly a treadle rod 33 through which the presser-foot may be lifted by connections hereinafter to be described.
- 20 For driving the main shaft 13 the following driving mechanism may be employed, with which is incorporated a stopping contrivance capable of making an adjustment between running adjustment and stopping 25 adjustment. The illustrated driving mechanism and stopping contrivances are not herein claimed *per se*, as they form the subject of prior Patent No. 1,085,093, issued January 20, 1914, which patent may be referred to 30 for more complete details of structure and operation.

The power shaft 41 may be driven by belt pulleys. This shaft extends forwardly and rearwardly, and in front of it stands a 35 cross shaft 46. Rotation is transmitted from shaft 41 to shaft 46 by a variable speed transmitter of the face friction type involving a friction disk 47 on the shaft 41 and a friction wheel 49 on the shaft 46. The wheel 40 slides upon its shaft by a spline 50 and the shaft is supported in bearings 51. At the right end of the shaft 46 is a pair of helical gears 52 by which the rotation is transmitted to the upright shaft 53, having a similar pair 45 of helical gears 54 by which the rotation is transmitted to the main shaft 13.

For effecting the axial adjustment of the friction wheel 49, whether to change the speed of the machine or to stop the machine 50 in accordance with said prior patent, a collar 55 is attached to the friction wheel, this collar affording a groove for a ring 56 engaged by the upper end of bell crank 57 and whose horizontal arm at the extremity has a 55 slotted connection 58 to a vertical rod 65. A spring 66, inclosed in barrel 67, tends to lift the rod 65 and thereby adjust the variable speed transmitter to full speed position. At the upper end of rod 65 is a connection 60 by which the rotation of the main shaft may effect an adjustment of the transmitter toward zero, so that the main shaft effects its own stoppage. This connection, which is normally disconnected, but may be connected 65 at suitable times, for example, at will, com-

prises a cam follower or stud 68 on the rod 65 and a cam disk 69 having a spiral groove 70, as seen in Fig. 8. The cam 69 is mounted on a short shaft 71, so as to move axially, and is toothed at 72 around its periphery to engage a gear 73 on the main shaft 13. The spiral groove 70 is such that, when the cam 69 is slid to the right, the stud 68 enters the groove 70, which causes the stud and the rod 65 to descend until the transmitter has attained zero adjustment, whereupon all of the mentioned parts come to rest. It will be understood that the friction disk 47 is continuously rotating, but that, when the machine is stopped, the parts 49, 46, 53, 13, 73 and 80 69 simultaneously come to rest.

In order to effect this stopping action at will, a grooved collar 74 is attached to the stopping cam 69 and is provided with connections to a knee lever 75, which may be 85 thrown at will to slide the cam 69 to right or left. When slid to the right the machine is brought, without shock, to rest, as described. When slid to the left, the cam and follower disengage and thereupon the spring 66, 90 which has been compressed during the stopping action, reasserts itself to gradually shift the friction wheel across the disk, thereby restoring the machine to full speed.

Convenient connections between the lever 95 75, moved at will, and the collar 74 comprise a bell crank 76, whose upper portion engages the collar and whose horizontal arm is jointed to a link 77 extending downwardly to where it is jointed to a second bell crank 10 lever 78, whose downward arm engages a slide 79 connected by a short link 80 to the knee lever 75. When the knee lever is thrown to the right, the parts 79, 80, are thrown to the left, link 77 is lifted and the cam 69 is moved to the right to stop the machine, and the reverse of these movements restarts the machine.

The cam groove 70 of cam 69 may have an inner concentric portion 81 to assist engaging with the follower, followed by an eccentric portion 82 corresponding substantially to a half turn of the cam or a full turn of the main shaft, and finally a concentric outer portion 83 at the proper distance from the center to bring the follower 68 and the parts connected with it to zero or stopping adjustment.

Now will be first described the presser-foot connections and the intermittent clamping or locking means therefor, and thereafter the means whereby the stoppage of the machine unclamps or unlocks the presser-foot to permit the lifting thereof and the extraction of the work.

Referring to Figs. 2 and 4, the top of the treadle rod 33 is provided with a projection 100. A short arm 101 has its forward end pivoted to the head of the rod to give it guidance in its up-and-down movements.

The projection 100 stands directly over a stud 102 upon the forward end of arm 104 fast upon the cross shaft 103, which takes part in controlling the amount of thread measured. When the treadle is depressed, the rod 33 brings the projection 100 into contact with the stud 102, so as to swing the shaft 103 of the arm 104 downward. This action tends to lift the presser-foot through a link 105, connecting the arm 104 with the rear arm or extension 106 of the presser-foot 24. Ordinarily, however, the depression of the treadle and rod could not effect this lifting when the presser-foot is clamped under pressure. Spring 107 tends to rotate shaft 103 and hold the presser-foot on the work. The devices by which the presser-foot is intermittently clamped under pressure include a dog 110 engaging a rack 111 supported at the rear end of an arm 112 which is connected by a powerful spring device 113 with the rear extending arm 106 of the presser-foot; while the arm 106 at its rear end is provided with a rack 115 engaged by a triple dog 114. Springs 116, 117, tend to hold the dogs against their racks. A cam lever 118, operated from groove 119 in cam disk 17 through stud 120, serves to intermittently clamp and release the presser-foot. During the formation of each stitch the lever 118 is forcibly depressed, and, after the feeding movement, is forcibly lifted. When the lever 118 is depressed, its heel disengages the dog 114, while the dog 110, being pivoted to the lever 118, is at the same time disengaged. When the lever is lifted, dog 110 forces upwardly the rack 111 and arm 112 imposes the heavy spring pressure of 113 upon the presser-foot, whereupon the triple dog 114 clamps or locks the parts in this position.

For disengaging the dogs to unclamp or unlock the presser-foot at other times than upon the lowering of the lever 118, the following devices may be employed: An unclamping lever 121 is loosely mounted upon the same pin or pivot 123 as that carrying the triple under-dog 114. The lever 121, which is in the shape of a bell crank, has an upward arm 122, which, when thrown rearward, contacts and presses the pins 124 and 125 respectively of the upper and underdogs, so as to throw both dogs out of engagement with their racks. The horizontal arm of the lever 121 is shown connected by a downward rod 126 to that portion of the mechanism which serves to automatically unclamp the presser-foot upon the stoppage of the machine. From the above description, it will be seen that the depression of the rod 126 swings the bell crank lever 121 to disengage the dogs, thus leaving the presser-foot free to be lifted, whereupon the treadle 32 can be thrown by the operator to lift the presser-foot.

The means whereby the stoppage of the machine effects the pulling down of the rod 126 for this purpose is shown generally in Fig. 1, and more particularly in Figs. 5, 6 and 7.

It has been explained that, when the operator throws the knee lever 75, the machine is brought to a stop by the adjustment of the transmitter 47, 49, to zero position. By reason of this stopping action the bell crank lever 57 is thrown and, for convenience, the motion of the bell crank lever is taken advantage of for attaining the end in view. Attached to the bell crank or the stud carrying it is a third arm 127 connected by a link 128 to a hooked rod 129, the hook of which consists of an offset portion at the top. The hooked rod moves down whenever the machine is stopped, and is adapted to make engagement with the rod 126 at the proper time, so as to pull the latter down for unclamping the presser-foot. The hook and rod are shown disengaged in Fig. 1, but engaged in Figs. 5 and 6.

Normally the rod 126 is pushed up by spring 130, the lower end of the spring abutting against a fixed platform 131 and the rod having a block or collar 132 thereupon. As seen in Fig. 7, the spring's platform 131 is held by a fixed standard 133 extending downwardly from a fixed frame member 134.

The engagement and disengagement between members 129 and 126 is effected by a horizontal sliding shoe 135, fitted within a groove in front of the block 132. The shoe is moved from the right-hand position of Fig. 1 to the left-hand position of Fig. 6, and vice versa, through a pin 136 forwardly projecting from the shoe and engaging a vertical slot in a block 137 extending downwardly from the link 80, which connects the knee lever 75 with the slide 79.

The operation of the described parts is that, when the knee lever is thrown from the left-hand position, with the parts as indicated in Fig. 1, to the right-hand position, as in Figs. 5 and 6, the link 80 and connected parts move to the left to connect the stud and cam 68, 69, whereby the main shaft 13 effects its own stoppage. At the same time the link 80, carrying the downward block 137, moves the sliding shoe 135 to the left beneath the hook 129. Thereupon, as the machine comes to rest, the down movement of the hook causes it to engage and pull down upon the shoe, and therefore the block 132 and rod 126, for unclamping the presser-foot, so that the work can thereupon be withdrawn from under the latter.

The described mechanism permitting the engagement and disengagement of parts 135 and 129 constitutes a convenient means of restoring the presser-foot clamping devices or dogs to their normal or operative condi-

tion. When the knee lever is thrown to the left for starting the machine, the shoe 135 is immediately slid to the right and thereby withdrawn from beneath the hook, so that the spring 130 may reassert itself to lift the rod 126, thereby permitting the re-engagement of the presser-foot operating pawls and dogs. The presser-foot mechanism is thereby instantaneously rendered operative, so that the presser-foot will be properly clamped during the opening stitches and without waiting for the transmitter and bell crank 57 to resume their full speed adjustment.

15 Since it is obvious that in some cases the presser-foot might be stationary and the work-support relatively movable, these parts may both be termed, for convenience, work engaging members, and the invention could 20 be applied in both aspects. As shown, the presser-foot is the relatively adjustable member.

25 The automatic unclamping device 121 hereof is distinguished from the clamping and unclamping lever 118, since the latter operates intermittently at every stitch, while the former operates only after a plurality of stitches and preferably only upon 30 stoppage of the stitching mechanism. The connections 73, 69, 68, 65, between the main shaft 13 and the bell crank 57 constitute a single means for effecting the stoppage of the machine and also the unclamping of the work-engaging member. These parts and 35 the bell crank operate through the variable speed transmitter, which constitutes a stopping means and, through the contrivance, including the engagers or hooks 129, 135, which operates the unclamping device, for 40 these purposes. The knee lever 75 constitutes a controller which, when thrown, causes the operation of the stopping means and the unclamping device. The arm 127, while automatically actuated, is movable 45 only during the active stopping or starting of the machine, but not during the normal running, and this is the automatic part chosen for acting through the connections 129, 136, etc., for operating the unclamping 50 device. Each dog, 110, 114, may be considered a clamp, one for applying pressure and the other for locking the presser-foot, and the whole, together with the cam lever 118, constitute the clamping means for the 55 presser-foot. The controller or lever 75, in its adjustment toward the right, first initiates the stoppage of the stitching, and then operates the unclamping device as the stitching ceases, while its left-hand adjustment 60 first restores the unclamping device and then causes normal stitching to resume.

65 It will thus be seen that there has been described a sewing machine embodying the improvements and attaining the objects and advantages above recited, and other advan-

tages therein will be apparent to those skilled in the art. Since many matters of design, arrangement, detail and other features may be variously altered without departing from the invention, no limitation to such features is intended excepting so far as specified in the appended claims.

What is claimed is:

1. In a sewing machine, the combination of stitching mechanism, mechanism including a driven shaft for operating the stitching mechanism, an adjustable work-engaging member, adapted to be firmly clamped upon the work, automatic connections timed with the stitching cycle for unclamping said member during each stitch, and reclamping it, and maintaining it clamped as the stitch is set, a stop motion operative after the formation of a plurality of stitches for slowing the forward rotation of the driven shaft and then bringing it from its forward rotation to a final stop in a definite position, automatically operating connections for unclamping without lifting said member during the final forward shaft movement in the stopping operation by said stop motion, and means subsequently operable at will for lifting said member.

2. In a sewing machine, the combination of stitching mechanism, mechanism for driving the stitching mechanism, an adjustable work-engaging presser-foot, means for clamping said presser-foot upon the work, mechanism for stopping the machine, a presser foot unclamping device, means for intermittently operating the unclamping device during stitching, a single means for operating both the stopping mechanism and the unclamping device and means subsequently operable at the will of the operator for removing said presser-foot from the work.

3. In a sewing machine, the combination of stitching mechanism, mechanism for driving the stitching mechanism, an adjustable work-engaging presser-foot, means for clamping said presser-foot upon the work, mechanism for stopping the machine, a presser foot unclamping device, means for intermittently operating the unclamping device during stitching, a single means for operating both the stopping mechanism and the unclamping device, the same being operable at will and means subsequently operable at the will of the operator for removing said presser-foot from the work.

4. In a sewing machine, the combination of stitching mechanism, mechanism for driving the stitching mechanism, an adjustable work-engaging member, means for clamping said member upon the work, an unclamping device, means for intermittently operating the unclamping device during stitching, a stopping means, and connections actuated by said stopping means for actuat-

ing said unclamping device, whereby said member is unclamped as the stitching ceases, and means subsequently operable at the will of the operator for removing said member 5 from the work.

5. In a sewing machine, the combination of stitching mechanism, mechanism for driving the stitching mechanism, an adjustable work-engaging member, means for 10 clamping said member upon the work, an unclamping device, a stopping means for slowing and finally stopping the stitching mechanism from its forward drive in a definite position, and a controller having 15 separate connections for operating both said stopping means and unclamping device, whereby said member is unclamped as the forward drive of the machine ceases.

6. In a sewing machine, the combination 20 of stitching mechanism, mechanism for driving the stitching mechanism, an adjustable work-engaging member, means for clamping said member upon the work, including a pressure-applying clamp and a locking 25 clamp, an unclamping means adapted to release both clamps, a stopping means for finally stopping the stitching action from its forward operation, and a single controller for operating said stopping means and said 30 unclamping means, whereby as the forward drive of the machine ceases the said member is released, and means subsequently operable at the will of the operator for removing said member from the work.

35 7. In a sewing machine, the combination of stitching mechanism, mechanism for driving the stitching mechanism, an adjustable work-engaging member, means for clamping said member upon the work, an unclamping 40 device, a stopping means, and connections actuated by said stopping means for actuating said unclamping device, whereby said member is unclamped as the stitching ceases, the described elements constructed and arranged 45 to permit the reclamping of said member with the resumption of stitching and means operable at will while the machine is stopped for removing said member from the work and restoring it to the work 50 prior to the restarting of the machine.

8. In a sewing machine, the combination 55 of stitching mechanism, mechanism for driving the stitching mechanism, an adjustable work-engaging member, means for clamping said member upon the work, including a pressure-applying clamp and a locking clamp, an unclamping means adapted to release both clamps, a stopping means for stopping the stitching action, and a single 60 controller for operating said stopping means and said unclamping means, whereby as the stitching ceases the said member is released, the described elements constructed and arranged to permit the reclamping of said 65 member with the resumption of stitching

and means operable at will while the machine is stopped for removing said member from the work and restoring it to the work prior to the restarting of the machine.

9. In a sewing machine, the combination 70 of stitching mechanism, mechanism for driving the stitching mechanism, an adjustable work-engaging member, means for clamping said member upon the work, an unclamping device for throwing the clamping means out of engagement, a stopping means for slowing and finally stopping the stitching mechanism from its forward drive in a definite position, and a controller having 75 separate connections arranged in one adjustment to first initiate the stoppage of stitching and then operate the unclamping device as the stitching ceases, and in another adjustment to first render the unclamping device inoperative and then cause normal 80 stitching to resume.

10. In a sewing machine, the combination 90 of stitching mechanism, mechanism including a variable speed transmitter for driving the stitching mechanism, an adjustable work-engaging member, means for clamping said member upon the work, and means operative at suitable times for adjusting said transmitter to zero and for automatically effecting the unclamping of said member. 95

11. In a sewing machine, the combination 100 of stitching mechanism, mechanism including a variable speed transmitter for driving the stitching mechanism, an adjustable work-engaging member, means for clamping said member upon the work, an unclamping device, normally inoperative connections from a running part or shaft for both adjusting the transmitter to zero and operating said unclamping device, and a controller for rendering said connections operative at suitable times whereby the stitching thereupon ceases and the member is unclamped. 105

12. In a sewing machine, the combination 110 of stitching mechanism, mechanism including an adjustable transmitter for driving the stitching mechanism, an adjustable work-engaging member, means for clamping said member upon the work, an unclamping device, an automatically movable part, connections extending from said device to said automatically movable part, and a single controller for controlling said connections and said transmitter. 115

13. In a sewing machine, the combination 120 of stitching mechanism, mechanism including an adjustable transmitter for driving the stitching mechanism, an adjustable work-engaging member, means for clamping said member upon the work, an unclamping device, a controller for controlling the running or stopping adjustment of said transmitter, a pair of engagers, as 129, 135, between an automatic part and said device, 130

and means whereby the controller engages said engagers upon the stoppage and disengages them upon resumption of stitching.

14. In a sewing machine, the combination of stitching mechanism, mechanism including an adjustable transmitter for driving the stitching mechanism, an adjustable work-engaging member, means for clamping said member upon the work, an unclamping device, connections whereby a running part of the machine may adjust said transmitter to zero, a controller governing the operative or inoperative condition of said connections, a contrivance actuated by the adjustment of the transmitter to zero for operating said unclamping de-

vice, and means whereby said controller also governs the operativeness or inoperativeness of said contrivance, such that for one adjustment of the controller the contrivance is 20 rendered operative and said connections stop the machine and operate the unclamping device, while a reverse adjustment renders the contrivance inoperative, and restarts the machine.

25 In testimony whereof I affix my signature in presence of two witnesses.

AUGUST R. SCHOENKY.
